UNITED STATES PATENT OFFICE.

CHARLES BAYER, OF NEW YORK, N. Y.

PIANO-FORTE DAMPER-ACTION.

SPECIFICATION forming part of Letters Patent No. 354,618, dated December 21, 1886.

Application filed September 16, 1886. Serial No. 213,714. (No model.)

To all whom it may concern:

Be it known that I, CHARLES BAYER, a citizen of the United States, residing at New York, in the county and State of New York, have 5 invented a new and Improved Piano - Forte Damper-Action, of which the following is a specification.

This invention relates to damper-actions for piano-fortes, and it more especially refers to 10 bearings of damper-cranks or lifting-bars.

This invention consists in the improvement hereinafter more fully specified.

In the accompanying drawings, Figure 1 represents a longitudinal view of part of a piano-forte main action-rail with the damper crank or lifting-bar attached. Fig. 2 is a section at line *a a*, Fig. 1, at an enlarged scale. Fig. 3 is a side view of the bearing at an enlarged scale. Fig. 4 is a top view of the same.

20 A is the main action-rail, made of wood of any approved form, and to which description of rails my invention more particularly refers, although the same is equally applicable to any other description of rails.

25 B is the damper-crank or lifting-bar applied to said rails, provided with the usual lifting-arm controlled by the treadle, (not shown in the drawings,) and *b b* are the pivots on which said crank or bar turns. These pivots are carried by bearings C.

30 Each bearing C, preferably cast of a circular form, as shown in the drawings, is provided at its lower surface with a circular projection, *d*, and at its face with a socket, *e*, to receive the 35 pivots *b*, or rather the cloth bushes entered within said socket and receiving the pivots through them. The circular projection *d* fits into a corresponding countersunk hole made in the rails when the damper-crank has been 40 fitted to the main action-rail, and thus secures the bearing C in its proper place, which is

then fastened to the rail by screws *n n*. The end of the cloth bushes may be lapped downward partly around the projection *d* to fill the countersunk hole in the rail, and thus insure 45 a perfectly-tight fit. To facilitate this, this projection *d* is placed on one side of the plate C, directly underneath the socket *e*. (See Figs. 3 and 4.) It will thus be observed that the countersunk hole in the rail need not to fit 50 very close the projection *d*, the plate C, lying upon the surface of the rail, covering any irregularity.

I am aware that similar plates described in the patent of Wessel, Nichel, and Gross, No. 55 210,381, have been used; but in that arrangement the main rail has to be gouged out for the lower part of the socket, and again for clearance of the crank part of the bar, besides which particular care has to be taken in 60 countersinking the hole into which the plate fits, and to trim the outside margin of said plate, so that the same will fit the countersunk hole, while by my improved plate only a hole has to be countersunk, and any irregularity will 65 be covered by the plate, improving not only the appearance of the rail, but at the same time saving considerable work and expense in fitting the same.

I claim—

The combination of the main action-rail A, and the damper-crank or lifting-bar B, having pivots *b*, with the plate bearings C, having circular projections *d* on the under side, and sockets *e* on its top or face surface, to receive suitable cloth bushes, and the pivot *b*, substantially as described.

CHARLES BAYER.
